Atty.

UNITED STATES PATENT OFFICE.

JOHN B. CARROLL, OF OAK PARK, ILLINOIS.

ADVERTISING OR DISPLAY DEVICE.

Application filed May 25, 1925. Serial No. 32,673.

This invention relates to that class of advertising or display devices or articles which are adapted to be used for advertising or for similar or other purposes.

5 The principal object of the invention is to provide a simple, economical and efficient advertising or display device or article of manufacture adapted to be used for advertising or similar or other purposes.

10 Other and further objects of the invention will appear from the following description and claims, and from an inspection of the accompanying drawings, which are made a part hereof.

15 The invention consists in the features, combinations, details of construction and arrangement of parts herein described and claimed.

In the accompanying drawings—

20 Figure 1 is a plan view showing an outer enclosing or enveloping sheet member or blank as it would appear before being folded over the inner movable member, and showing an inner movable member formed 25 of sheet material, as it would appear before being folded and before being enclosed by or within the outer member;

Fig. 2 is a similar view of the parts shown in Fig. 1, but showing one of the marginal 30 leaves of the outer member infolded over the inner member, and opposite marginal leaves or folded marginal portions of the inner movable sheet member folded over adjacent opposite margins of the said infolded leaf 35 of the outer enveloping member;

Fig. 3 is a front or plan view of the device shown in Figs. 1 and 2, showing the outer marginal leaf of the outer enclosing or enveloping member folded over the inner sheet 40 member and inner or infolded leaf of the outer member, and showing the opening in one side or in one leaf of the outer enveloping member adapted to expose parts of the inner movable sheet member and parts of 45 the infolded marginal leaf of the outer or enveloping member or sheet;

Fig. 4 is a similar front or plan view of the device shown in Fig. 3, showing the inner movable sheet member in a position into 50 which it is adapted to be moved from the position in which it is shown in Fig. 3; and

Fig. 5 is a central sectional view taken on line 5—5 of Fig. 3, looking in the direction indicated by the arrows.

55 In constructing an improved advertising or display device or article of manufacture

in accordance with my invention, I provide an outer enclosing or enveloping member 1 which is, by preference, formed of a folded sheet of card-board or similar sheet material 60 and comprises a back or central sheet body portion 2 having a front outer marginal leaf or folded marginal portion 3 on or attached to and by preference integral with one margin 4, and having, by preference, an infolded marginal leaf or folded marginal portion 5 on or attached to and by preference 65 integral with an opposite margin 6. An opening 7 is formed, by preference, in the outer marginal leaf or folded marginal portion 3 of the outer enveloping member or envelope 1, said leaf being cut away to form said opening. The leaf 3 thus has opposite side marginal portions 9 and 10 on opposite sides of said opening, and has top and bottom margins 11 and 12 at the top and bottom extremities of said opening, thus forming a suitable frame for the opening 7.

The marginal leaf 5 of the outer enclosing or enveloping member, which is adapted to be folded inward, is, by preference, provided with an opening 13 therein; said marginal leaf 5 having a connected side margin 14 on one side of said opening and a side margin 15 on the opposite side of said opening 13 from the margin 14, and top and bottom margins 16 and 17, respectively, one above and the other below said opening 13. (See Figs. 1 and 2.)

An inner movable sheet member 18 is movably or slidably mounted inside of the outer enclosing or enveloping member 1, and consists of or comprises, by preference, a main sheet body portion 19 of slightly less width than the back or sheet body portion 2 of the outer envelope 1, said body portion 19 having opposite parallel margins or folded marginal portions 20, 21 each having a corresponding marginal leaf 22 and 23, respectively, connected with or formed integrally 90 with said margins respectively. The folded margin 20, with which the top marginal leaf 22 is connected, and the folded margin or marginal portion 21 with which the marginal leaf 23 is connected, are thus disposed transversely with respect to the direction of movement of the movable inner member, and are at right angles with respect to the opposite guiding margins 4 and 6 of the outer enveloping member 1.

The opposite folded margins or marginal portions 20 and 21 of the inner movable sheet

member 18 are spaced apart a sufficient distance from each other so as to admit therebetween the sheet 5 of the outer envelope member 1 which in its infolded position, as shown in Fig. 2, extends across the opening 7 in the outer enveloping or enclosing member 1 and between and in position to be overlapped by said upper and lower marginal leaves 22 and 23 respectively. The inner movable sheet member 18 is readily movable from the position in which it is shown in Fig. 4, to the initial or normal position in which it is shown in Figs. 2 and 3, and also in Fig. 5.

The marginal sheet 5 of the outer enveloping member 1 having been folded inward over the movable sheet 18 and into position to extend transversely across the opening 7 and to be overlapped by the marginal leaves 22 and 23 of the inner movable sheet member 18, as shown in Fig. 2, the outer marginal leaf 3 is then folded over the infolded leaf 5 and over the leaves 22 and 23 of the inner movable sheet member 18, and the outer margin 9 of the outer marginal leaf 3 is attached to the margin 14 of the infolded leaf 5 or to the margin 6 of the back or sheet body portion 2 of the outer enclosing or enveloping member 1, by means of glue or other suitable adhesive material or connecting means, the opposite ends between which the folded marginal leaves 22 and 23, respectively are located, being left open so as to permit free movement of the inner movable member 18 between the opposite parallel guiding margins or marginal portions 4 and 6, which are connected or closed so as to form suitable guiding margins between which the inner movable member 18 is adapted to be shifted or moved.

The flap or tongue 24, for operating the inner movable member, is, by preference, formed in one integral piece with the marginal leaf or flap 23 on the same extremity of said inner movable member, said leaf 23 being bent or folded from the position in which it is shown in Fig. 1 to the position in which it is shown in Fig. 2, thereby permitting the flap 24 to project beyond the folded margin of the leaf 23 and movable member 18 and between notched portions 25 in the leaf 3 and back or sheet body portion 2 respectively, so as to provide convenient means for enabling the operator to grasp the flap or tongue 24 and operate the inner movable member or sheet 18.

From the foregoing it will be readily understood by those skilled in the art to which this invention relates, that by moving the inner movable member or sheet 18 from the position in which it is shown in Figs. 2 and 3 to the position in which it is shown in Fig. 4, the leaf 22 on the member 18 will cover the upper or adjacent marginal or trans-

verse upper portion 16, and any picture, part of a picture, characters, words or printed matter thereon, and the lower or opposite marginal leaf 23 will uncover and expose or display the adjacent or corresponding marginal portion or surface of the lower part 17 of the leaf 5, and anything printed, impressed or otherwise placed on said part 17 of said leaf. And by moving the inner movable leaf 18 in an opposite direction, or from the position in which it is shown in Fig. 4 to the position in which it is shown in Figs. 2 and 3, the part 16 of the leaf 5 will be exposed or uncovered and the part or marginal surface portion 17 of said leaf 5 will be covered or concealed from view.

It will also be readily seen that when the inner movable sheet 18 is in the position shown in Figs. 2 and 3, one part of the surface of the inner movable sheet 18—for example, the central part or surface portion 26 of the said movable sheet 18—will be exposed or uncovered by the opening 13 in said infolded marginal leaf 5 of the outer enveloping member 1. It follows that when the inner movable sheet member 18, with its marginal leaves or folded marginal portions 22 and 23, is moved from the position shown in Figs. 2 and 3, the part 26 of the inner movable sheet member 18 which was previously uncovered by the opening 13 will be covered or concealed by the marginal leaf 23, and another and different part of the surface of the inner movable sheet member 18 will be uncovered or exposed to view, such for example, as the part or surface portion 27, as shown in Fig. 4.

The top part of the picture shown in the accompanying drawings is on the upper marginal leaf or flap 22 of the inner movable sheet or slide 18, the middle part of said picture being on the part 27, above the word "It", the word "It" being on the part 26, and the word "Gets" being on the bottom marginal leaf or flap 23 of said inner sheet 18. The word "Pays" is on the reverse side of margin 16; and the lower part of the picture and the words "Golden Eggs" are on the reverse side of the margin 17 of inner leaf 5. (See Fig. 1, also Figs. 2, 3, and 4.) It will thus be seen that the outer enveloping member 1, of which the inner leaf 5 forms a part; and the inner movable sheet or slidable member 18, which includes parts 22, 23, 26 and 27, each have printed or display matter thereon which is adapted to be exposed or uncovered when the display matter or printed matter on the adjacent portion of the other one of said members is concealed, and vice versa.

I claim:

1. In a device of the class described, the combination of an outer enveloping member formed of sheet material and having an opening in one side thereof, said member

having opposite guiding marginal portions adjacent to corresponding margins of said opening, an inner sheet member movably mounted inside of said outer enveloping member and between said guiding marginal portions of the same, a marginal leaf on said inner movable sheet member, and movable with the same into and out of exposed position within said opening, said marginal leaf being adapted to overlap and alternately cover and expose a surface portion of said enveloping member within said opening and having one edge connected with and extending along a corresponding marginal portion 10 of said inner movable sheet member in transverse relation to the direction of movement of the latter, said elements including means for limiting the movement of the inner sheet member with respect to the outer enveloping member, said outer enveloping member and inner movable sheet member each having display matter thereon adapted to be exposed when the display matter on an adjacent portion of the other one of said 25 members is concealed.

2. In a device of the class described, the combination of an outer enveloping member formed of sheet material and having an opening in one side thereof, said member having opposite guiding marginal portions adjacent to corresponding opposite margins of said opening, an inner sheet member movably mounted inside of said outer enveloping member and between said guiding marginal portions of the same, marginal leaves on said inner movable sheet member, and movable with the same into and out of exposed position within said opening each of said marginal leaves being adapted to overlap and alternately cover and expose a surface portion of said enveloping member within said opening, each of said leaves having one edge connected with and extending along a corresponding marginal portion 40 of said inner movable sheet member transversely with respect to the direction of movement of said inner movable sheet member, said elements including means for limiting the movement of the inner sheet member with respect to the outer enveloping member, said outer enveloping member and inner movable sheet member each having display matter thereon adapted to be exposed when the display matter on an adjacent portion of the other one of said members is concealed.

3. In a device of the class described, the combination of an outer enveloping member formed of sheet material and having an opening in one side thereof, said member having opposite closed guiding marginal portions adjacent to corresponding opposite margins of said opening, an inner folded sheet member movably mounted inside of said outer enveloping member and between

said guiding marginal portions of the same, said inner folded sheet member comprising opposite marginal leaves on and integral with opposite parallel margins of said inner movable sheet member, said marginal leaves being movable alternately into exposed position across said opening, said integral leaves of said inner movable sheet member being disposed transversely with respect to the direction of movement of said inner movable sheet member, and adapted to alternately cover and expose adjacent surface portions of said enveloping member within said opening and retaining means on the inside of the outer enveloping member and adapted to be engaged by opposite marginal portions of said inner movable sheet member respectively and acting to limit the movement of said movable sheet member with respect to the outer enveloping member, said outer enveloping member and inner movable sheet member each having display matter thereon adapted to be exposed when the display matter on an adjacent portion of the other one of said members is concealed.

4. In a device of the class described, the combination of an outer enveloping member formed of sheet material and having an opening in one side thereof, said member having opposite connected guiding marginal portions adjacent to corresponding opposite margins of said opening, an inner sheet member movably mounted inside of said outer enveloping member and between said guiding marginal portions of the same, said inner movable sheet member comprising a body portion and integral folded marginal leaf portions on opposite margins of said movable sheet member, each of said marginal leaf portions being movable with said movable sheet member into and out of exposed position across said opening, and an inner leaf inside of and having one edge connected with said outer enveloping member, said inner connected leaf having a surface portion provided with display matter thereon, said surface portion being adapted to extend across said opening and between the body portion and folded leaf portions of said inner movable sheet member in position to be alternately covered and exposed by said marginal leaves of said inner movable sheet member.

5. In a device of the class described, the combination of an outer enveloping member formed of sheet material comprising a main sheet body portion having integral inner and outer marginal leaves on opposite margins thereof, the outer one of said marginal leaves having an opening therein, and the inner one of said leaves being adapted to extend across said opening, and an inner sheet member movably mounted and comprising a main sheet body portion having integral

opposite marginal leaves in movable overlapping relation to corresponding parallel margins of the inner leaf of said outer enveloping member, said marginal leaves being adapted to alternately cover and expose adjacent surface portions of said last mentioned inner leaf, said leaf and overlapping marginal leaves having display matter thereon adapted to be alternately covered and exposed within said opening by the movement of said inner movable sheet member.

6. In a device of the class described, the combination of an outer enveloping member formed of sheet material comprising a main sheet body portion, integral inner and outer marginal leaves on and attached to opposite margins of said main sheet body portion, the outer one of said leaves having an opening therein and the inner one of said leaves being adapted to extend across said opening, an opening in the inner leaf and an inner sheet member movably mounted inside of said outer enveloping member and comprising a main sheet body portion which extends across the opening in said inner leaf and between the said inner leaf and the back of the enveloping member, integral opposite marginal leaves on said inner movable sheet member and in overlapping movable relation to corresponding parallel margins of the inner leaf of said outer enveloping member and inside of said outer marginal leaf of said outer enveloping member and adapted to be moved into and out of exposed position within the opening in said outer marginal leaf, said marginal leaves on said movable member being adapted to alternately cover and expose adjacent surface portions of said overlapped inner leaf, and said overlapping marginal leaves and the inner leaf member overlapped thereby having display matter thereon adapted to be alternately covered and exposed within the opening in the outer leaf of the enveloping member.

7. In a device of the class described, the combination of an outer enveloping member formed of sheet material comprising a main sheet body portion, integral inner and outer marginal leaves on and connected with

opposite folded marginal portions of said main sheet body portion, the outer one of said leaves having an opening therein and the inner one of said leaves being adapted to extend across said opening, and one of the margins of said outer leaf being attached to an adjacent margin of said inner leaf, and an inner sheet member movably mounted inside of said outer enveloping member, and having marginal flaps along the upper and lower edges of said inner movable sheet member, each in overlapping movable relation to a corresponding adjacent margin of the inner leaf of said outer enveloping member and adapted to alternately cover and uncover a portion of the surface of said inner leaf of said outer enveloping member, said outer enveloping member and inner movable sheet member each having display matter thereon adapted to be exposed when the display matter on an adjacent portion of the other one of said members is concealed.

8. In a device of the class described, the combination of an outer enveloping member formed of sheet material comprising a back, inner and outer marginal leaves on and connected with opposite margins of said back, the outer one of said leaves having an opening therein and the inner one of said leaves being adapted to extend between said back and said outer leaf, and across said opening an inner sheet member movably mounted inside of said outer enveloping member, and marginal flaps along the upper and lower edges of said inner movable sheet member and in transverse relation to the direction of movement of said movable sheet member, said marginal flaps being adapted to alternately cover and expose adjacent surface portions of the inner leaf of said outer enveloping member within said opening in the outer leaf, said marginal flaps and said inner leaf of said enveloping member having display matter thereon adapted to be alternately covered and exposed by the movement of the inner movable sheet member.

Signed at Chicago, in the county of Cook and State of Illinois this 19th day of May, 1925.

JOHN B. CARROLL
